Attys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,119.

Specification of Letters Patent. Patented Aug. 9, 1921.

Application filed January 16, 1920. Serial No. 351,790.

To all whom it may concern:

Be it known that I, FRED S. CARR, a citizen of the United States, and a resident of Newton, in the county of Middlesex, Commonwealth of Massachusetts, have invented 5 an Improvement in Separable Fasteners, of which the following description, in connection with the accompanying drawings, is a specification, like characters on the drawings 10 representing like parts.

This invention pertains to improvements in separable fasteners, and more particularly, though not exclusively, to an improvement in the securing of such fasteners to 15 fabrics.

In the drawings, which show a preferred embodiment of one form of my invention:

Figure 1 is an elevation of two pieces of fabric held together by a preferred form of 20 fastener;

Fig. 2 is a section on the line 2—2 of Fig. 1;

Fig. 3 is a section on the line 3—3 of Fig. 2, the cloth carrying the socket being 25 omitted;

Fig. 4 is an elevation taken from the right of Fig. 2, showing the preferred form of socket-securing means;

Fig. 5 is a side elevation of the part shown 30 in Fig. 4; and

Fig. 6 is an enlarged section of the socket and socket-securing means as applied to the fabric being taken on the line 6—6 of Fig. 1.

Referring to the drawings and to the preferred form of my invention, I have shown 35 a stud 7 which may be secured to the fabric in the manner shown and claimed in my co-pending application Serial No. 351,780, filed herewith. The socket 8 may contain any 40 suitable form of spring means, but I prefer to utilize the spring 9 coöperating with a notched aperture 10, as shown in my pending application Serial No. 307,111, filed June 27, 1919.

Only a small portion of the socket rim 11 is utilized to hold in position the spring 9, and I prefer to utilize other portions of said 45 socket rim coöperating with clenching elements, hereinafter more fully described, to 50 secure the socket to its fabric. I may conveniently perform this by throwing up in the base of the socket casing clenching surfaces 12 adapted to deflect clenching prongs 13 after the latter have been pressed through 55 the socket-carrying fabric 14 and to turn

said prongs beneath the flanged-over rim 11 of the socket casing.

The socket-securing element 15 which carries the prongs 13 is preferably flanged at its edges to throw the socket-carrying fabric 60 14 toward the front face of the socket casing. The prongs 13 may conveniently be struck down from the metal forming the socket-securing part 15, as is best shown in Fig. 4. 65

As previously stated, the aperture 10 in the socket casing is preferably notched to provide a lateral lock, as in my copending application above referred to. I may conveniently utilize this notch as a means for 70 locating the socket casing relative to the applying tool, and I preferably utilize the applying tool to locate the socket-securing part 15 by providing a non-symmetrical aperture 16 in that part. The tool for applying the socket may be provided with irregular projections, as shown in my copending application filed herewith, so that proper co-ordination between the prongs 13 and the clenching parts 12 may be insured. 80

It will be understood that I use the word "fabric" in its broader sense to include not only woven materials, but any flexible carrying medium.

While I have shown and described a preferred form of one embodiment of my invention, it will be understood that changes involving omission, substitution, alteration and reversal of parts, and even changes in the mode of operation, may be made without 90 departing from the scope of my invention, which is best defined in the following claims.

Claims:

1. A metallic-secured socket for separable 95 fasteners comprising, in combination, a casing providing a plate having a stud-receiving aperture therethrough and an upwardly and inwardly flanged peripheral rim, a casing-securing part on the opposite side of the 100 socket-carrying fabric from said casing and providing fabric-penetrating prongs, and anvil portions on said casing to turn said prongs outwardly beneath said inwardly flanged peripheral rim when said casing and securing part are pressed toward one another with the fabric between them.

2. A metallic-secured socket for separable 105 fasteners comprising, in combination, a casing providing a plate having a stud-receiving 110

- ing aperture therethrough and an upwardly and inwardly flanged peripheral rim, a casing-securing part on the opposite side of the socket-carrying fabric from said casing and 5 providing fabric-penetrating prongs, and anvil portions on said casing to turn said prongs outwardly beneath said inwardly flanged peripheral rim when said casing and securing part are pressed toward one another with the fabric between them, said casing containing a spring retained therein by said inwardly flanged peripheral rim and said anvil portions arranged in non-interfering 10 relation to said spring.
- 15 3. A metallic-secured socket for separable fasteners comprising, in combination, a casing providing a plate having a stud-receiving aperture therethrough and an upwardly and inwardly flanged peripheral rim, a casing-securing part on the opposite side of the 20 socket-carrying fabric from said casing and providing fabric-penetrating prongs, and
- anvil portions on said casing to turn said prongs outwardly beneath said inwardly flanged peripheral rim when said casing and securing part are pressed toward one another with the fabric between them, said casing containing a spring retained therein by said inwardly flanged peripheral rim and said casing and casing-securing part each provided with 25 locating means to preclude assembly of said casing and casing-securing part with said prongs in interfering relation to said spring.
4. A socket for separable fasteners comprising, in combination, a spring-containing 30 casing, having a flanged-over rim, a socket-securing part having prongs projecting therefrom for engagement beneath the rim of said casing, said socket-securing part being dished to throw the socket-carrying 35 fabric toward the face of the socket.

In testimony whereof, I have signed my name to this specification.

FRED S. CARR.
